UNITED STATES PATENT OFFICE

WALTER M. CROWTHER, OF BEAVER, PENNSYLVANIA

INGOT MOLD INSERT

Application filed October 25, 1929. Serial No. 402,427.

REISSUED

Broadly the object of my invention is the provision of means for producing more perfect ingots.

In the manufacture of iron or steel, as an example, molten metal from the open hearth or other refining device is carried in a ladle and is poured therefrom into a series of ingot molds to form ingots. These ingot molds may be hollow structures of cast iron, six feet or more in height, and they rest upon ingot stools which close the bottoms thereof. Although the tap hole of the ladle is held as close to the mouth of the ingot mold during pouring as is practicable, the molten metal has to fall a considerable distance, and initially strikes the ingot stool with sufficient force to splatter over the cold interior walls of the mold. The splattered metal chills instantly, forming hard nodules or splinters which, as the metal rises in the mold, become embedded in the sides of the growing ingot. They cause defects when the ingot is rolled, and most frequently must be removed before the rolling or blooming operation.

An object of my invention is the provision of means for preventing the production of slivered ingots by eliminating or preventing the initial splashing of the metal.

Again, the portions of the molten metal which first come in contact with the cold mold walls chill there, and form a hard shell within which the remaining metal may still be molten or plastic. As the metal cools and contracts there are thus set up strains in it which produce internal flaws and militate against the production of perfect rolled products. When a square ingot is poured, the outer shell is frequently still plastic enough when the strains appear to relieve them somewhat by deforming slightly. Thus hollow sided ingots are produced which may successfully be worked. In cylindrical ingots, however, the same opportunity for deformation in the shell is not present, so that, in general, the production of cylindrical ingots has been highly unsatisfactory. Another object of my invention therefore is to provide means to delay somewhat the initial freezing or chilling of the metal so that more perfect ingots may be formed. Through

the use of my invention entirely satisfactory cylindrical ingots may be produced.

Still other objects of my invention are the provision of means to accomplish the objects outlined hereinabove, which means will not delay the production of ingots and will not be cumbersome to handle or expensive to use.

These and other objects of my invention which may be pointed out hereinafter or will be apparent to one skilled in the art upon reading this specification I accomplish by that certain construction and arrangement of parts of which I shall now describe a preferred embodiment reference being made to the drawings which accompany this specification.

In the drawings which are semi-diagrammatic:

Figure 1 is a cross section through an exemplary ingot mold fitted with my insert, and showing metal being poured therein.

Figure 2 is a horizontal cross section along the lines *a—a* of Figure 1.

In the practice of my invention, I employ an insert placed within the ingot mold and adapted both to break the initial falling of the molten metal from the ladle and also to provide initial insulation for the ingot mold walls to delay the freezing in the metal.

I have shown in Figure 1 an ingot mold 1 resting upon the ordinary ingot stool 2. Molten metal is poured therein from a ladle 3 as will be readily understood by those skilled in the art. Although the insert to which I use may take different forms without departing from the spirit of my invention, the preferred embodiment—preferred because while perfectly satisfactory in use, it is easy to handle and practically negligible in cost, is in the form of a heavy paper insert indicated generally at 4. It may conveniently be in the form of a closed bag of such size that its bottom 5 will lie over that portion of the ingot stool top which rests beneath the open lower end of the ingot mold. It will preferably have sides 6 of such a size and configuration as will fit reasonably closely the walls of the ingot mold 1 for a substantial portion of their length. The bag is sealed with some air in it but not sufficient to fill it

completely, so that the top of the bag may be pushed down within the outer walls so as to form a re-entrant pocket 7. It will be understood that the bags may be made and shipped flat either in the form of a cone or cut and pasted so as to form in situ the upstanding bag portion and the re-entrant pocket. It is most convenient to form it in pyramidal shape with a sealed bottom. In use, one of the bags will be partially inflated and sealed at the smaller end. It may then be placed upon an ingot stool and the ingot mold lowered over it, or it may be inserted in the ingot molds from above. Thereupon with a pole or the like, a workman will push the upper and smaller closed end of the bag down inside the ingot mold. This will have the effect of compressing the air in the sealed bag so as to expand the outer walls of it into contact with the inner walls of the ingot mold, and will also have the effect of pushing the closed smaller end of the pyramid down into the interior of the pyramid to form the re-entrant pocket. It is advantageous to have the lower end of the pocket extend down within a comparatively short distance of the mold bottom for a reason which will hereinafter become apparent. Various other types of inserts may be used. In the type shown, by reason of the fact that the insert is a sealed bag, air is entrapped in the interior of it as at 8 and acts as a cushion as will hereinafter be explained. To utilize the cushioning effect of entrapped air is advantageous because it allows me to use thinner materials for my insert and consequently to use my invention more economically and conveniently. However, it would be possible to rely upon the natural stiffness or resiliency of the material employed so that the bag need not be sealed. With a material of sufficient resiliency, a bag open at the bottom may be employed; but it is better to have a covering of the material of the insert over the portion of the stool top which forms the floor of the ingot mold. My ingot mold inserts may of course be made of a variety of materials other than paper with perfect satisfaction, although in general with greater expense.

In use, the operation of my invention is as follows: A stream of molten metal 9 as is the usual practice, is allowed to run from the ladle 3 into the ingot mold 1. When my insert is in place, the metal instead of dropping a distance of say 8 feet and striking the cold hard floor of the ingot mold, strikes the lower end of the re-entrant pocket 7 in my insert. The force of its descent is broken or cushioned by the effect of the entrapped air, and a quantity of the molten metal will accumulate in the re-entrant pocket in the very short space of time before the paper burns through. When the paper does burn through however, the metal is let out upon the floor of the ingot mold from a distance above it which is com-

paratively short. Thus there will be practically no splash and the metal will be initially introduced quietly into the mold. This will explain the advantage of having the lower end of the re-entrant pocket comparatively near the bottom of the mold. No particular distance however, is necessary in the practice of my invention.

Even if the metal falling upon the ingot mold 4 should splash to some extent, the splatters of metal instead of hitting the cold floor and walls of the mold will hit the outer walls and bottom of my insert. The paper or other material used for the insert acts as an insulator and delays chilling and freezing of the metal. It will be noted that the walls of my insert extend for considerable distance up the interior walls of the ingot mold. After the bottom has gently been covered with molten metal, the tendency to splash is greatly reduced for the reason that the stream of metal is no longer falling upon a cold hard surface but instead is falling into a pool of molten metal. Such splattering of the metal as occurs from time to time will strike the paper walls of the insert until the pouring of the ingot is in general more than half finished. As the pouring progresses however, the walls of the ingot mold become heated sufficiently to minimize the danger of defects in the ingot both from splattering and from too rapid chilling at the outer surfaces. As has been pointed out during the pouring, the paper walls of the insert act as insulators to delay the freezing of the metal at the mold walls.

It will be understood that the actions thus described all occur very quickly. The molten metal of course ignites and consumes the insert so that no structure of it is left in the final ingot.

Various modifications may be made in my invention without departing from the spirit of it.

Having thus described my invention, what I claim as new and desire to secure by Letters Patent, is:

1. An insert for an ingot mold comprising a sealed bag having portions adapted to contact the walls and bottom of an ingot mold and a portion for arresting an initial quantity of molten metal poured into the mold, side portions being destructible by the heat of the molten metal to deposit said arrested metal upon the floor of an ingot mold.

2. An insert for an ingot mold comprising a sealed bag having a bottom and sides adapted to contact the bottom and interior walls of an ingot mold, and a re-entrant portion forming a pocket.

3. An insert for an ingot mold comprising a resilient downwardly extending pocket to catch an initial quantity of molten metal poured into the mold, said pocket being de-

structible to release said metal after initially arresting it.

4. An insert for an ingot mold comprising a sealed bag of heavy paper having portions adapted to contact the bottom and interior walls of an ingot mold and serve as initial insulators therefor, and a portion adapted to form a re-entrant downwardly projecting pocket the lower end of which approaches the bottom of said insert.

5. An insert for an ingot mold comprising a bag of flexible, heat destructible material, said bag adapted to be sealed, and having one portion adapted to be thrust down into the 15 remaining portions to form a reentrant pocket, the remaining portions of said bag being adapted to contact the floor and interior walls of an ingot mold.

6. An insert for an ingot mold comprising 20 a substantially pyramidal bag of heavy paper, the apex of the pyramid thrust downwardly into the interior of said bag to form a re-entrant pocket, said bag having sufficient entrapped air therein to serve as a resilient 25 support for said re-entrant pocket to hold it above the bottom of said bag.

7. In an insert for an ingot mold, a structure comprising means whereby it is stationed a material distance up from the floor of the 30 mold, to arrest the initial fall of the molten metal, said structure being adapted to disintegrate and deposit the arrested molten metal quietly upon the floor of the ingot mold.

8. In an insert for an ingot mold, a de- 35 structible structure comprising means whereby it is stationed a material distance up from the floor of the mold, to arrest the initial fall of the molten metal into the mold.

9. In an insert for an ingot mold, a de- 40 structible air-supported structure comprising means whereby it is stationed a material distance up from the floor of the mold, to arrest the initial fall of the molten metal into the mold.

45 10. In an insert for an ingot mold, a de- structible structure confining air and having a part supported by the confined air, to arrest the initial flow of the molten metal into the mold.

50 11. In an insert for an ingot mold, a hollow destructible structure having a pocket in its top.

55 12. In an insert for an ingot mold, a hollow shell with an inturned upwardly opening pocket in its top.

60 13. In an insert for an ingot mold, a hollow shell with an inturned upwardly opening pocket in its top, the sides of said pocket converging downwardly from the upper edges of the pocket.

WALTER M. CROWTHER.
